W. G. LONG

PLUG FOR WELLS

Filed June 30, 1924

FIG. 1.

FIG. 2.

Inventor

W.G. Long.

By

A. Stobrig Attorney

UNITED STATES PATENT OFFICE.

WILLIAM G. LONG, OF TULSA, OKLAHOMA.

PLUG FOR WELLS.

Application filed June 30, 1924. Serial No. 723,257.

This invention relates to certain new and useful improvements in plugs for wells and more particularly to plugs expressly adapted to be used in connection with oil and gas wells for plugging the well below the oil producing sand and is what is known in the art as a dry hole plug.

A further object of the invention is to provide a plug which is formed of ductile material having a peripheral groove in which is adapted to be arranged a packing so that when the ductile material forming the core of the plug is compressed, the packing is compressed so as to completely close the well.

A still further object of the invention is to provide a plug which when placed in position within a well and subjected to a series of impacts of the well drilling tool, the plug will expand so as to close the well and in connection with the packing in the groove, a water-tight joint will be formed so as to cut off water at the desired point in the well.

Other and further objects and advantages of the invention will be hereinafter set forth and the novel features thereof defined by the appended claims.

In the drawings,

Figure 1 is a side elevation of a plug constructed in accordance with my invention showing the same in a well before being set; and

Figure 2 is a similar view showing the plug set so as to completely close the well.

In carrying out my invention I employ a cylindrical body 1 having a peripheral spiral groove 2 formed intermediate its ends to provide a seat for a packing 3 which is preferably formed of lead wool, which is manufactured in coils in rope form and the packing is wound in the groove and the ends cut off.

The formation of the groove in the body provides heads 4 and 5 and when the body is lowered into the well with the packing in position, the same can be readily set in the desired position by the well drilling tool.

The body is preferably formed of malleable material, such as lead, so that when it is subjected to a series of impacts, the malleable material will be compressed so as to decrease the diameter of the spiral groove, which forces the packing material outwardly and as the body is compressed lengthwise,

the diameter of the same is increased so that the hole of the well is completely closed.

By forming the body of lead, the well drilling tool can be readily attached to the ends for lowering the same if desired and after the same has been lowered by raising the well drilling tool and allowing the same to drop so as to deliver a series of impacts to the head 5, the malleable body will be expanded and at the same time the grooves will be partly closed so as to expand the lead wool packing outwardly beyond the surface of the body so as to produce a water tight joint.

While I have shown a plug constructed with a spiral groove, I am aware that grooves of other formations could be used, as my invention consists broadly in providing the plug formed of a body of malleable material having a groove in its periphery to receive a packing, which packing is expanded as the malleable material is compressed.

From the foregoing description it will be seen that I have provided a dry hole plug for wells which can be used for plugging the casing or for plugging the hole below the casing and therefore I do not wish to limit myself to the use of said plug at any desired point as I am aware that the same could be used in connection with a packer.

What I claim is:—

1. A plug for wells comprising a circumferentially grooved body formed of malleable material, a packing arranged within said groove, said body being adapted to be compressed to expand the body and compress the packing material carried by the groove.

2. A plug for wells comprising a malleable body having a spiral groove and a cord of packing material arranged within said groove.

3. A plug for oil wells comprising a cylindrical body formed of malleable material having a spiral groove intermediate its ends, a strip of packing material arranged within said groove, said body being adapted to be compressed to increase the diameter thereof and to compress the packing in said groove beyond the periphery of said plug.

In testimony whereof I hereunto affix my signature.

WILLIAM G. LONG.
